UNITED STATES PATENT OFFICE.

JESSE A. LANDIS, OF EATON, OHIO.

SOUND REFLECTOR.

Application filed January 15, 1925. Serial No. 2,615.

This invention aims to provide novel means whereby the sound proceeding from a signal of any kind, such as a locomotive whistle or an automobile horn may be amplified, controlled and directed.

It is within the province of the disclosure to improve generally and to enhance the utility of devices of that sort to which the invention appertains.

Although a preferred form of the invention has been shown in the drawings, it will be understood that a mechanic, working within the scope of what is claimed, may make such changes as the skill of his calling may dictate, without departing from the spirit of the invention.

In the accompanying drawings:—

Figure 1 shows in section, a device constructed in accordance with the invention; and

Figure 2 is a front elevation.

In carrying out the invention, there is provided a support 1 wherewith is assembled an audible signal 2, disclosed in the form of a whistle although any kind of a fluid-pressure-actuated signal may be employed. A pipe 3, communicating with the support, furnishes fluid of any kind, such as steam or air, to operate the signal 2. The orifices in the signal 2, from which the sound proceeds, are marked by the numeral 4.

The invention contemplates the use of a parabolic reflector. The reflector may be constructed as desired, and may be supported in any desired way. As shown in the drawings, but not of necessity, the reflector 5 is supported at its axis only, on the member 1, the reflector being held in place on the member 1 by nuts 6, threaded on the part 1 and binding the central portion of the reflector between them, the construction being such that the reflector may be adjusted forwardly and backwardly, thereby so to locate

the orifices 4 that the results hereinafter described may be attained. It is suggested that the reflector 5 be made out of metal or other material which is thin enough so that it can vibrate responsive to the sound proceeding from the orifices 4 in the signal 2.

In practical operation, three sorts of sound waves are given out, to wit, those proceeding directly from the orifices 4, those which are refracted by the member 5, and those which are produced by a vibration of the reflector. The result is that when the signal 2 is sounded, a volume is produced which cannot be attained in the absence of the device which forms the subject matter of this application.

What is claimed is:—

In a device of the class described, a parabolic reflector, a tubular support, a fluid-pressure-actuated signal carried by the support, the support extending through the reflector, the reflector being adjustable longitudinally of the support, toward and away from the signal, and holding devices adjustable longitudinally of the support and cooperating with the reflector to retain the reflector in adjusted positions, the holding devices engaging the reflector in a limited area about its axis, so that practically all of the reflector will be free to vibrate, the holding devices constituting means for so positioning the signal within the contour of the reflector that two sorts of sound waves will be produced, to wit, those proceeding directly from the signal and those reflected by the reflector, the signal being sufficiently thin so that it can vibrate and produce a third kind of sound waves when the signal is operated.

In testimony that I claim the foregoing as my own, I have hereto affixed my signature.

JESSE A. LANDIS.
